WRENCH

Marshall N. Kincaid, West Hartford, Conn., assignor to The Billings & Spencer Company, a corporation of Connecticut

Application December 17, 1938, Serial No. 246,525

6 Claims. (Cl. 81—58)

My invention relates to wrenches.

It has among its objects to provide an improved friction wrench, and, more particularly, an improved so-called double acting, or reversible, wrench of this type. A further object of my invention is to provide improved reversing mechanism for such a wrench adapted to hold the parts thereof in different relations, while being readily and quickly operable by the operator to reverse the possible operation of the wrench whenever desired. Further objects include the provision of an improved body member and improved cooperating friction members of an improved compact and long wearing construction mounted on said body member and cooperating therewith and with one another in an improved manner, and also having improved reversing means herein including improved cooperating abutment and spring means on said body member and one of the friction elements respectively. These and other advantages of my improved construction will, however, hereinafter more fully appear.

In the accompanying drawing, I have shown for purposes of illustration one embodiment which my invention may assume in practice.

In the drawing:

Figure 1 is a plan view of a wrench embodying this form of my improvements;

Fig. 2 is a detailed side elevation of the working portion of the wrench shown in Figure 1, the handle being broken away to facilitate illustration;

Fig. 3 is a sectional view on line 3—3 of Figure 1;

Fig. 4 is a plan view of the construction shown in Figure 1, with the parts in reversed relation, the handle here being broken off to facilitate illustration;

Fig. 5 is a detail exploded view of the parts of the wrench, certain of the same being shown spaced above their operative position to facilitate illustration, and

Fig. 6 is a detail perspective view of this form of reversing means.

In this construction, it will be noted that I have shown a wrench comprising cooperating friction members, generally indicated at 1 and 2, of which the member 1 herein carries a usual depending polygonal turning portion 3 adapted to be received in any suitable socket, while the portion 2 is provided with a handle 4 adapted to swing the same about a pivot 5 on a frame member or body element 6 in which both the elements 1 and 2 are carried; these elements 1, 2

and 6 herein being of an improved construction and having improved reversing mechanism associated therewith, all as hereinafter more fully described.

Referring more particularly to the member 1, it will be noted that the same is provided with upper and low annular flanges 7 and 8 which close the opposite ends of a round aperture 9 through the member 6, and also preferably have their outer surfaces flush with the top and bottom surfaces of that member. Further, it will be observed that an annular friction surface 10 of reduced diameter is provided on this member 1 between the flanges 7 and 8, and that the polygonal turning portion 3 which is rotatable with this member 1, projects axially from the outer face of the flange 8. It will also be observed that the frame member 6 is provided with flat laterally projecting parallel top and bottom portions 11 and 12 also flush with the outer faces of the flanges 7 and 8 and herein having side edges converging toward the outer end of these portions. As shown, a transverse slot 13 is also provided between these portions 11 and 12, while a communicating aperture 14 opens into the aperture 9 and provides access to the friction surface 10 on the member 1. Further, it will be noted that the friction member 2 is mounted in the slot 13 and has its inner end 15 extended through this aperture 14 into contact with the friction portion 10 on the member 1 between the flanges 7 and 8 thereon. Note further that this inner end 15 is arcuate and symmetrical in such manner as in different angular relations of the members 2 and 6 to enable the opposite end portions 15a and 15b of this portion 15 selectively to project through the aperture 14 at opposite sides of the center thereof and engage the surface 10 with a camming action and thereby make reverse operation possible. Moreover, it will be observed that herein this member 2 is pivoted on the portions 11 and 12 on a screw 5 which extends through a registering hole 16 in the member 2 and is threaded, as at 17, in the portion 12 of the member 6, while having a beveled head 18 seated in the portion 11 in such manner as also to be flush with the top thereof. As a result of this construction, it will be evident that the member 2 will be moved with its handle 4 about its pivot 5 in reverse directions to rotate the member 1 in the desired direction, the members 6 and 2 also moving together about the axis of the member 1 through the camming action established between the surfaces 15 and 10 on the members 1 and 2.

Herein, it will also be observed that improved reversing means are provided. These, as shown, include a prong, or projection, 19 on the free end of the portion 11 on the frame member 6. As shown, this projection is symmetrically disposed on opposite sides of the center line of the latter member and also provided with straight side surfaces 20. Further, it will be observed that the handle 4 carries a plate spring member, or finger, 21 extending longitudinally thereof and herein suitably fixed to the handle at its remote end, as at 22, and provided intermediate its ends with an upwardly curved portion 23 and with an adjacent downwardly curved portion 24 between said portion 23 and an extremity 25 having edges 26 converging toward said extremity. As shown, a longitudinally grooved guide and abutment portion 27 is also provided in the handle 4 below the portion 24 in such manner as to permit the latter portion to be depressed so that the edges 26 of the extremity 25 will be disposed below the projection 19, while the walls of the groove provide abutments preventing swinging of the spring in all positions thereof. Thus, whenever the raised portion 23 is pressed down by the operator, end portion 25 will free the projection 19, while when the portion 23 is released, the resiliency of the spring 21 will return the portion 25 to its normal or projection engaging position. Further, it will be apparent that the surfaces 26 provided on the projection 19 are thus adapted to abut opposite edge portions 26 on the spring 21 in the different angular relation of the members 2 and 6 shown in Figs. 1 and 4. If desired, a shallow indentation may be provided in the surfaces 20 to receive these edges 26.

In the operation of my improved construction, it will be evident that with the parts in the position shown in Figure 1, when the handle 4 is pulled down, the surfaces 15 and 10 engaging as indicated, will cause rotation of the member 1 and socket engaging member 3; the handle thereafter being swung reversely after the manner of a ratchet wrench, with the end portion 15a of friction surface 15 alternately moving back over the surface 10 and gripping the latter to effect intermittent rotation of the members 1 and 3 in a screwing in or tightening direction. Further, when the portion 23 of the spring 21 is depressed by the operator's thumb, it will also be noted that the projection 19 will be released, so that the parts may be turned into the position shown in Figure 4 in which the end portion 15b engages surface 10. Also, following release of the spring, one of the edges 26 thereon will rise automatically in the path of the adjacent face 20 on the projection 19 in such manner as to hold the parts 2 and 6 in this new angular relation. With the parts in this position, it will also be understood that when the handle 4 is operated successively reversely, a releasing rotation of the work engaging member 3 will result.

As a result of my improved construction, it will be observed that it is made possible for the direction of operation to be reversed readily and quickly as desired. It will also be evident that the action of the spring 21 as it rises up alongside the surfaces 20 on the projection 19 is such as automatically to prevent relative lateral movement between the elements 2 and 6. It will further be observed that the member 2 continues effectively to position the member 1 in all positions of the wrench without requiring any further positioning means therefor, the edge of the curved frictional surface 15 of the member 2 always be-

ing disposed between the flanges 1 and 3 on the member 1, in such manner as to maintain the latter member in operative position in the frame member 6. Moreover, it will be evident that, whenever the screw 5 is removed, the member 2 is withdrawn, in such manner as then to permit the member 1 to drop down through the aperture 8 and be readily separated from the frame member 6. Further, it will be observed that, while the above advantages are obtained, the member 6 is maintained of a simple and compact construction, while the reversing spring means is free from strain at all times during operation of the wrench and also so disposed below the top of the member 6 as to protect the spring against damage or accidental operation. It will be observed that to provide my improved construction, only a small number of simple and inexpensive parts are required, all of which may be separately made and readily assembled to produce an exceedingly simple construction of rugged character, while at the same time enabling any of the parts which become worn to be readily and quickly replaced when desired. These and other advantages of my improved construction will, however, be clearly apparent to those skilled in the art.

While I have in this application specifically described one embodiment which my invention may assume in practice, it will be understood that the same is shown for purposes of illustration, and that the invention may be modified and embodied in various other forms without departing from its spirit or the scope of the appended claims.

What I claim as new and desire to secure by Letters Patent is:

1. In a wrench, a body member, cooperating camming members mounted thereon and having means operative upon reversely swinging one cooperating member to grip and release the other member, and means for positioning said body and swingable camming member in different angular relations to reverse the direction of said gripping and releasing movements including a longitudinally extending prong on said body member and adjustable detent means on said swinging member comprising a cooperating resilient finger fixed against lateral swinging movement relative to said member and swingable therewith into positions wherein opposite sides of said finger are selectively engageable with opposite sides of said prong in different angular relations, said swinging camming member having a handle and said finger comprising a plate spring carried thereon and disposed longitudinally thereof and movable downwardly toward said handle out of the lateral planes including said prong during movement of said swingable camming member and body member into different angular positions.

2. In a wrench, a body member, cooperating camming members mounted thereon and having means operative upon reversely swinging one cooperating member to grip and release the other member, and mechanism for positioning said body and swingable camming member in different angular relations to reverse the direction of said gripping and releasing movements including a longitudinally extending prong on said body member and a cooperating oppositely extending resilient finger fixed against lateral swinging movement relative to said swingable camming member and having a free end projecting beyond the end of said prong and swingable

- with said camming member in lateral planes including said prong, said finger having angularly related faces selectively engaging opposite sides of said prong in different angular positions of the parts and the free end of said finger being movable against its resilience in a direction transverse to said lateral planes and out of said planes during relative movement of said swinging camming member and body between said different angular positions.
5. In a wrench, a body member, cooperating camming members mounted thereon and having means operative upon reversely swinging one cooperating member to grip and release the other member, and means for positioning said body and swingable camming member in different angular relations to reverse the direction of said gripping and releasing movements including a longitudinally extended projection on said body member and adjustable detent means on said swinging member engaging opposite sides of said projection in different angular relations, said swinging camming member having a longitudinally grooved handle and said detent means including a longitudinally disposed plate spring 10 depressible into the groove therein to clear said projection and abutting against the opposite side walls of said groove when engaging said projection.
15. In a wrench, a body member, cooperating camming members mounted thereon and having means operative upon reversely swinging one cooperating member to grip and release the other member, and means for positioning said body and swingable camming member in different angular relations to reverse the direction of said gripping and releasing movements including a longitudinally extended projection on said body member and 20 adjustable detent means on said swinging member engaging opposite sides of said projection in different angular relations, said swinging camming member having a longitudinally grooved handle and said detent means including a longitudinally disposed plate spring 25 depressible into the groove therein to clear said projection and abutting against the opposite side walls of said groove when engaging said projection.
25. In a wrench, a body member, cooperating camming members mounted thereon and having means operative upon reversely swinging one cooperating member to grip and release the other member, and means for positioning said body and swingable camming member in different angular relations to reverse the direction of said gripping and releasing movements including a longitudinally extended projection on said body member and 30 adjustable detent means on said swinging member engaging opposite sides of said projection in different angular relations, said swinging camming member having a longitudinally grooved handle and said detent means including a longitudinally disposed plate spring 35 depressible into the groove therein to clear said projection and abutting against the opposite side walls of said groove when engaging said projection.
35. In a wrench, a body member, cooperating camming members mounted thereon and having means operative upon reversely swinging one cooperating member to grip and release the other member, and means for positioning said body and swingable camming member in different angular relations to reverse the direction of said gripping and releasing movements including a longitudinally extended projection on said body member and 40 adjustable detent means on said swinging member engaging opposite sides of said projection in different angular relations, said swinging camming member having a longitudinally grooved handle and said detent means including a longitudinally disposed plate spring depressible into the groove therein to clear said projection and abutting against the opposite side walls of said groove when engaging said projection.

idly connected to and fixed against lateral swinging movement relative to said swinging member and said portion being movable out of the plane of said portion to permit swinging of said swinging camming member.

5. In a wrench, a body member, cooperating camming members mounted thereon and having means operative upon reversely swinging one cooperating member to grip and release the other member, and means for positioning said body and swingable camming member in different angular relations to reverse the direction of said gripping and releasing movements including a longitudinally extended prong on said body member and longitudinally disposed adjustable detent means 10 on said swinging member comprising a cooperating finger centrally disposed thereon having one end rigidly fixed thereto, said finger being fixed against lateral swinging movement relative to said swinging member and having its free end 15 disposable bodily on opposite sides of said prong.

6. In a wrench, a body member, cooperating camming members, one rotatably mounted on said body member and the other pivoted thereon and disposable in different angular relations thereto, said pivoted member having a longitudinally grooved handle, an annular cam face on said rotatable camming member, and a cooperating arcuate cam face on said pivoted member having means on opposite sides of a median line 20 extending through said face and the pivot of said member for selectively gripping said annular face in said different angular relations, and means for maintaining said body member and pivoted member in a selected angular relation including a projection on said body member movable across the groove in said handle, and a compressible spring on said pivoted member selectively engageable with opposite sides of said projection and having a depending portion disposed in said groove and engageable with the side walls thereof in different positions of said projection.

MARSHALL N. KINCAID.
